WASHING MACHINE AND DRIVE THEREFOR

Bryan W. Chapin, Tully, N. Y., assignor to Easy
Washing Machine Corporation, Syracuse, N. Y.,
a corporation of Delaware

Application July 3, 1948, Serial No. 36,835

20 Claims. (Cl. 68—23)

1

This invention relates to washing machines, and more particularly to washing machines in which oscillatory agitating motion is employed, although the invention may be employed in other fields where a motion of a similar nature is desirable.

In an application Serial No. 793,159, filed December 22, 1947, there is disclosed a washing machine in which there is provided a resilient drive between the driving motor and the agitator or agitating basket; and provision is made therein for causing the motor to rotate a number of revolutions in one direction, reverse, and rotate in the other direction to provide the agitator oscillation.

The present invention constitutes an improvement over and variation of the invention disclosed in said application, in that provision is made for facilitating the reversal of the motor. In the aforesaid application, the motor is caused to stall, and subsequently to be started by storage of and delivery of energy stored in a spring, the motor being of the induction type and readily stalled in this manner, while continuously energized.

The present invention provides an arrangement wherein the motor is de-energized prior to stalling, and re-energized as soon as rotation is effected in the reverse direction. Through such an arrangement, heavy current peaks occurring when the motor is stalled, are eliminated.

An object of the present invention is to provide an oscillating drive of the type described, in which extreme peaks of current flow are eliminated.

A further object of the invention is to provide an oscillating drive of the type described, in which, by the elimination of high peaks in the current flow, the degree of oscillation may be varied.

Still another object of the invention is to provide an oscillating drive of the type described, in which the degree of oscillation may be readily varied, and in which the drive may be readily converted to continuous rotary motion.

Yet another object of the invention is to provide an oscillatory drive for washing machine agitation, and in which the agitation power may be readily varied.

A further object of the invention relates to the construction and arrangement of parts, whereby a rugged and economical drive of the type described results.

The above and other novel features of the invention will appear more fully hereinafter from the following detailed description when taken in conjunction with the accompanying drawings.

2

It is expressly understood that the drawings are employed for purposes of illustration only and are not designed as a definition of the limits of the invention, reference being had for this purpose to the appended claims.

In the drawings, wherein like reference characters indicate like parts:

Figure 1 is a vertical axis section of the invention showing its adaptation to a washing machine;

10 Figure 2 is a fragmentary side detail partly in section, taken on the line 2—2 of Figure 1, and illustrating one of the controls;

Figure 3 is a transverse section taken substantially on the line 3—3 of Figure 1;

15 Figure 4 is a broken transverse section taken substantially on the line 4—4 of Figure 1;

Figure 5 is a transverse section taken substantially on the line 5—5 of Figure 1, and illustrating an adjustment feature; and

Figure 6 is a circuit diagram for the apparatus.

Referring to the drawings, and more particularly to Figure 1, there is shown a tub 10 mounted upon a base 12 of inverted shallow cup shape, the latter being provided with a bottom plate 14 and a plurality of supporting feet 16. The tub 10 is provided with a drain outlet 18 which may be provided with a hose the free end of which may be elevated or lowered to retain wash water within or drain the tub, as is well understood in the art. The tub is provided with a suitable cover 20 which is removable for access thereto. The bottom 22 of the tub and the top 24 of the base 12 are provided with aligned central apertures in which there is positioned a bearing support member 26, the same being provided with a shoulder 28 bearing against the top 24. The member 26 projects through said apertures and is provided with a nut 30 to clamp the tub bottom 22 to the top 24 of the base, suitable washers being provided to establish a leak-tight seal for the tub.

30 Projecting upward into the tub is a tubular member 32 rigidly secured in the support member 26, the tubular member 32 extending preferably beyond the height of the rim of the tub 10. The support member 26 may be integrally formed with an end plate 34 of a motor 36. The field 35 of the motor is clamped between the top end plate 34 and a bottom plate 38 by a plurality of clamp screws 40. The clamp screws also 35 secure the motor frame formed by the plates 34 and 38 to brackets 42 fastened to the skirt 44 of the base 12.

40 Within the field 35 is a rotor 46 mounted upon a sleeve 48, the lower end of which engages a thrust bearing 50 bearing against the frame mem-

50

55

ber 38. The rotor 46 is clamped upon the sleeve 48 between a shoulder 52 and nut 54. Extending through the sleeve 48 is a shaft 56 projecting below the thrust bearing 50 and extending upwardly beyond the end of the fixed tubular member 32. The upper end of the shaft 56 may be squared as at 58 and have securely fastened thereto a wash receiving basket 60 having an integral central upstanding sleeve 62 with an end flange 64 received by the squared end 58. A cap 66 threaded in the end of the shaft 56 is adapted to secure the basket 60 upon the shaft 56. It will be seen that the basket 60 is provided with one or more agitating vanes 68, and a plurality of perforations 70, so that the basket may function for both washing when given an oscillatory washing motion, and extracting when continuously rotated at suitable extraction speeds.

The sleeve 48 extends upwardly in the tubular member 32 a substantial distance and is provided with a roller bearing 72 acting to center the sleeve 48 upon the shaft 56. Abutting the end of the sleeve 48 is a second sleeve 74 extending upwardly along the shaft 56, the same being securely fastened and keyed thereto as at 76 adjacent the upper end of the sleeve. The sleeves 48 and 74 have reduced external diameter portions 78 and 80 throughout a substantial portion of their length to provide an annular cavity 82, in which there is positioned a relatively long coil spring 84. The upper end of the coil spring 84 is secured within the enlarged portion 86 as at 88, and the said enlarged portion forms a bearing as at 90 against the internal wall of the tubular member 32. The lower end of the spring is similarly secured in an enlarged portion 92 of the lower end of the sleeve 48, and the sleeve 48 is journaled in the support member 26 upon a roller bearing 94.

The lower end of the shaft 56 extending beyond the frame member 38 forms a journal 96 upon which is rotatably mounted a commutator plate 98. The commutator plate is supported upon a hub member having dog clutch teeth 102 in its under face. The plate 98 is restrained from rotation by a pancake type of spiral spring 104 having a plurality of turns, the outer of which is anchored as at 106 to the motor frame member 38. The inner end of the spring is anchored to a circular plate 108 having a circular beveled edge 110 suitably clamped by wedge blocks 112 fastened to the commutator plate 98. The blocks 112 are secured to the plate 98 by screws 114, so that the angular relation between the commutator plate 98 and the spring anchor plate 108 may be readily varied by loosening the wedge blocks, after which the wedge blocks may be securely clamped against the beveled edge 110 to preserve the adjustment.

The shaft 56 may be supported upon an end thrust ball 57 on the bottom plate 14, but the basket weight may be jointly carried by the shaft and compression of the spring 84.

A lower extremity of the shaft 56 contains a feather key or spline 116 upon which is slidably mounted a collar 118 having one or more dog teeth 120 of the commutator plate hub member previously described. The collar 118 is adapted to be axially shifted to engage or disengage the dog teeth by actuation of a lever 122 fulcrumed as at 124 and extending through an L-shaped notch 126 in the skirt 44 of the casing 12, the lever being provided with a suitable knob 128 at its extremity. The L-shaped notch 126 provides for movement of the lever knob from an upper position with the dog clutch teeth disengaged to a lower position where the clutch teeth become

engaged. A shoulder 130 in the slot 126 is adapted to retain the lever in the engaged position unless deliberately moved therefrom.

The commutator plate 98 is composed of insulation in which is imbedded a conducting plate 132 having arcuate segmental portions 134, 136 and 138 of graduated arcuate length. For convenience, the arcuate segmental portions increase in arcuate length with a decrease in radius. The conducting plate 132 is also provided with an annular conducting ring portion 140 located radially inwardly of the segmental portions described.

A brush holding bracket 142 extending transversely across and beneath the commutator plate 98, is rigidly mounted upon the skirt 44, and has affixed at the inner end thereof a rectangular brush 144 suitably secured to the bracket in an insulating sleeve 146. Slidably mounted upon the bracket 142 is a brush holder 148 mounting a brush 150 also suitably insulated as at 152. The brush holder 148 may be moved radially with respect to the commutator plate 98 by a bell crank lever 154 fulcrumed as at 155 on a skirt carried bracket 156. One end of the bell crank lever projects through a slot 158 and is provided with a handle 157. The slot 158 is provided with three notches 160, 162 and 164 to provide three positions in which the lever may be set manually. The other end of the bell crank is bifurcated at its end as at 166 to engage an ear 168 upon the sliding brush holder 148.

In Figure 6, there is diagrammatically shown an electrical circuit for operating the apparatus as described. The motor shown comprises the rotor 46 and a main field winding 170 as in a common single phase induction motor. Such a motor will rotate in either direction depending upon the direction in which the motor is started. A capacitor starting winding, including the coil 172 and condenser 174 is provided so that under ordinary circumstances, the rotor 46 will commence to turn in one direction. In circuit with the motor, is an over-all control switch 176 and parallel circuits 178 and 180 selectable at will by operation of the switch 182. The parallel circuit 180 includes the brushes 144 and 150 bearing against the commutator plate 132, and the circuit 178 consists of a bypass around said brushes. It will be seen that the circuit 178 would be equally effective if arranged merely as a shunt across the brushes 150 and 144. The circuit 178 is effective to cause the motor to commence rotation in the capacitor starting winding direction and to cause the motor to continue to rotate in that direction. Under such circumstances, the dog teeth 120 and 102 are disengaged as in the position shown in Figure 1. By providing a motor having a proper number of field poles, the basket 60 will be caused to spin at a predetermined speed satisfactory for extraction of water from laundry contained therein. A suitable speed for such purposes may be in the order of 600 or 900 R. P. M., as may be found desirable.

It will be noted that the motor rotor drives the basket 60 through the spring 84, the spring allowing the motor to start easily and thereafter drag the basket 60 with it. During the acceleration period, the motor rotor may be several revolutions ahead of the basket, but as speed is attained, this lead may decrease. The over-all effect, however, is a direct drive between the motor and the basket.

If the circuit is established through the brushes 144 and 150, and the circuit 178 opened, and the clutch teeth 120 and 102 engaged, the motor 146

will commence to rotate as previously described. As will be apparent, the spring 84 will again be torsionally stressed and cause the basket 60 to commence to rotate in the same direction. However, the basket is keyed to the shaft 56 and rotation of the shaft 56 is now restrained by the pancake spring 104. Thus, after the basket has rotated through an angle of possibly 90°, the spring 104 will have a restraining force sufficient to stall the basket and react through the spring 84 and stall the motor armature. The energy stored in the spring system will immediately upon stalling the motor armature tend to initiate rotation of the motor armature in the opposite direction, thus starting the motor and causing the same to gain speed in the opposite direction. The cycle thus described repeats itself, the motor carrying the basket in the opposite direction through the resilient coupling effect of the spring 84 until such basket has rotated a sufficient distance to torsionally stress the spring 104 in the opposite direction, whereupon the stalling sequence again takes effect.

The operation thus described is similar to that disclosed in the aforesaid application, and it will be apparent that as a torque is applied sufficient to stall the motor, the current consumption will increase, resulting in current peaks of low power factor which, while not creating any serious loss of energy, nevertheless may under certain circumstances be undesirable and cause heating. The commutator and brushes are adapted to eliminate the current peaks, since it will appear that as the pancake spring 104 becomes subjected to high torsional stress as the commutator and shaft 56 rotate, the commutator acts to break the circuit by rotating in one direction or the other. The plate 132 rotates out of range of the brush 150 and breaks the circuit to the motor prior to the actual stall thereof. At the same time, the motor is started as before in the reverse direction mechanically by the spring energy stored; and after it has been so started, the contact plate 132 again contacts the brush 150, thereafter energizing the motor and causing the motor to accelerate independently of the energy stored in the spring. Immediately thereafter, the springs pass through the neutral stress zone and the motor again commences to torsionally drive the basket 60 through the spring 84, storing energy in the spring at the same time. As previously described, as soon as the basket commences to rotate, the pancake spring thereafter passes through its neutral stress position, and thence becomes stressed resulting in the storage of energy. After the same is stressed to a high degree and the commutator rotated sufficiently, the circuit through the brush 150 and the conductor plate 132 is again broken. The stored energy is then effective to start the motor in the reverse direction.

It will be seen that by moving the brush 150 radially inward or outward from the position shown in Figure 4, the angle during which the circuit will be maintained will be enlarged or decreased. Thus, the angle through which the basket is oscillated may be readily varied and the severity of agitation changed to suit conditions. For example, for the washing of light fragile fabrics, rotation through a smaller angle may be desirable, whereas for fabrics subjected to great soil more violent agitation may be desired. Also, where a heavier load of laundry is being washed, greater agitation and energy may be required, which may be quickly supplied by moving the brush 150 inwardly for a greater angle of contact.

While the capacitative starting circuit tends to start the motor in one direction, it will be readily understood that such circuit does not prevent the motor from being mechanically started in the reverse direction, and once so started, the motor will run in such reverse direction although the torque in such reverse direction will necessarily lie slightly less than in the normal direction. Provision may be made to disconnect the starting circuit capacitative after initial starting has been completed, but in practice the operation is little affected by leaving the starting winding connected. In practice, the switch 182 may be directly activated by the lever 122; that is, the circuit 180 closed when the lever 122 is down and the circuit 178 closed when the lever is up.

With the capacitative starting circuit, the rotor of the motor which has considerable inertia initially oscillates through increasing angularity, until the commutator becomes effective to periodically break the circuit, and facilitate as well as regulate the oscillations and the angle of oscillation. The capacitative starting circuit lightly biases the motor at all times during its operation, and this bias has been found desirable if arranged to act in the direction such as to tend to wind the spring 84 rather than to unwind it. If desired, a high current capacitative starting winding may be used momentarily to start the motor in one direction, in which case, the initial starting torque is much greater, and full oscillations commence practically immediately, with the commutator effectively breaking the circuit and centrally the oscillation angle at the outset.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

- 45 1. In an oscillatory drive, in combination, an induction motor having a rotor, an energizing circuit for the motor, an anchor, resilient means connecting said rotor with said anchor, and means for opening the circuit to said motor upon the storage of a predetermined amount of energy in said resilient means.
- 50 2. In an oscillatory drive, in combination, an induction motor having a rotor, an energizing circuit for the motor, an anchor, resilient means connecting said rotor with said anchor, means for opening the circuit to said motor upon the storage of a predetermined amount of energy in said resilient means, and means for initially starting said motor in one direction.
- 55 3. In an oscillatory drive, in combination, an induction motor having a rotor, an energizing circuit for the motor, an anchor, resilient means connecting said rotor with said anchor, means for opening the circuit to said motor upon the storage of a predetermined amount of energy in said resilient means, and oscillatable driven means drivably connected to said resilient means at a point intermediate the connections of said resilient means with said rotor and anchor.
- 60 4. In an oscillatory drive, in combination, an induction motor having a rotor, an energizing circuit for the motor, an anchor, resilient means connecting said rotor with said anchor, means for opening the circuit to said motor upon the storage of a predetermined amount of energy in
- 65 70 75

said resilient means, means for initially starting said motor in one direction, and oscillatable driven means drivably connected to said resilient means at a point intermediate the connections of said resilient means with said rotor and anchor.

5. In an oscillatory drive, in combination, an induction motor having a rotor, an energizing circuit for the motor, an anchor, torsional means connecting said rotor with said anchor adapted to resist rotation of said rotor in either direction, means responsive to a predetermined torsion in either direction in said torsional means for opening the circuit to said motor.

6. In an oscillatory drive, in combination, an induction motor having a rotor, an energizing circuit for the motor, an anchor, torsional means connecting said rotor with said anchor adapted to resist rotation of said rotor in either direction, means responsive to the degree of torsion in said torsional means for opening the circuit to said motor, and means for initially starting said motor in one direction.

7. In an oscillatory drive, in combination, an induction motor having a rotor, an energizing circuit for the motor, an anchor, torsional means connecting said rotor with said anchor adapted to resist rotation of said rotor in either direction, means responsive to the degree of torsion in said torsional means for opening the circuit to said motor, means for initially starting said motor in one direction, and driven means connected to said torsional means at a point intermediate the connections of said torsional means with the rotor and anchor.

8. In an oscillatory and rotary drive, in combination, an induction motor having a rotor, an energizing circuit for the motor, an anchor, torsional means connecting said rotor with said anchor adapted to resist rotation of said rotor in either direction, means responsive to the degree of torsion in said torsional means for opening the circuit to said motor, means for initially starting said motor in one direction, driven means connected to said torsional means at a point intermediate the connections of said torsional means with the rotor and anchor, means for disconnecting from the anchor the portion of said torsional means between said driven means and rotor and means for shunting said circuit opening means.

9. In an oscillatory drive, in combination, an induction motor having a rotor, an energizing circuit for the motor, an anchor, torsional means connecting said rotor with said anchor, and means responsive to a predetermined angular movement of said torsional means for opening the circuit to said motor.

10. In an oscillatory drive, in combination, an induction motor having a rotor, an energizing circuit for the motor, an anchor, torsional means connecting said rotor with said anchor, means responsive to a predetermined angular movement of said torsional means for opening the circuit to said motor, and means for at will varying the amount of said predetermined angular movement.

11. In an oscillatory drive, in combination, an induction motor having a rotor, an energizing circuit for the motor, an anchor, torsional means connecting said rotor with said anchor, means responsive to the angular movement of said torsional means for opening the circuit to said motor, means for initially starting said motor in one direction, and driven means connected to said torsional means at a point intermediate the

connections of said torsional means with said anchor and rotor.

12. In an oscillatory and rotary drive, in combination, an induction motor having a rotor, an energizing circuit for the motor, an anchor, torsional means connecting said rotor with said anchor, means responsive to the angular movement of said torsional means for opening the circuit to said motor, means for initially starting said motor in one direction, and driven means connected to said torsional means at a point intermediate the connections of said torsional means with said anchor and rotor, means for disconnecting from said anchor the portion of said torsional means between said driven means and rotor and means for shunting said circuit opening means.

13. In an oscillatory and rotary drive, in combination, an induction motor having a rotor, an energizing circuit for the motor, an anchor, torsional means connecting said rotor with said anchor, means responsive to the angular movement of said torsional means for opening the circuit to said motor, means for initially starting said motor in one direction, driven means connected to said torsional means at a point intermediate the connections of said torsional means with said anchor and rotor, means for disconnecting from said anchor the portion of said torsional means between said driven means and rotor, means for shunting said circuit opening means, and means for at will varying the amount of said predetermined angular movement.

14. In an oscillatory and rotary washing machine drive, in combination, a tub, an induction motor having a rotor disposed beneath said tub and secured thereto, an energizing circuit for the motor, an anchor fixed with respect to said motor and tub, torsional means connecting said rotor with said anchor, means responsive to the angular movement of said torsional means for opening the circuit to said motor, means for initially starting said motor in one direction, a laundry containing basket within said tub connected to said torsional means at a point intermediate the connections of said torsional means with said anchor and rotor, means for disconnecting from said anchor the portion of said torsional means between said basket and said rotor, means for shunting said circuit opening means, and means for at will varying the amount of said predetermined angular movement.

15. In an oscillatory and rotary washing machine drive, in combination, a tub, an induction motor having a rotor disposed beneath said tub and secured thereto, an energizing circuit for the motor, an anchor fixed with respect to said motor and tub, torsional means connecting said rotor with said anchor, means responsive to the angular movement of said torsional means for opening the circuit to said motor, means for initially starting said motor in one direction, a laundry containing basket within said tub connected to said torsional means at a point intermediate the connections of said torsional means with said anchor and rotor, means for disconnecting from said anchor the portions of said torsional means between said basket and said rotor and means for shunting said circuit opening means.

16. In a washing machine, a base, an upstanding tubular column, a tub mounted around said column, agitating means journaled around said column, drive means extending through the column and connected to said agitating

means for rotation therewith, an induction motor in the base, a resilient connection from the motor to said agitating means, a commutator switch drivably connected to said drive means, and in circuit with said motor, an anchor, and torsional means connecting said drive means with said anchor.

17. In a washing machine, a base, an upstanding tubular column, a tub mounted around said column, a wash containing basket journaled around said column, drive means extending through the column and connected to said basket for rotation therewith, an induction motor in the base, a resilient connection from the motor to said basket positioned within said column, a commutator switch drivably connected to said drive means, and in circuit with said motor, an anchor, and torsional means connecting said drive means with said anchor, said commutator switch being adapted to open the circuit to said motor upon a predetermined angular movement of said drive means in either direction.

18. In a washing machine, a base, an upstanding tubular column, a tub mounted around said column, a wash containing basket journaled around said column, drive means extending through the column and connected to said basket for rotation therewith, an induction motor in the base including means for initially starting said motor in one direction, a resilient connection from the motor to said basket positioned within said column, a commutator switch drivably connected to said drive means, and in circuit with said motor, an anchor, a torsional means connecting said drive means with said anchor, clutch means for rendering said torsional anchor ineffective, and means for shunting said commutator switch, whereby said basket may at will be caused to oscillate or rotate continuously in one direction.

19. In a washing machine, a base, an upstanding tubular column, a tub mounted around said column, a wash containing basket journaled around said column, drive means extending

through the column and connected to said basket for rotation therewith, an induction motor in the base including means for initially starting said motor in one direction, a resilient connection from the motor to said basket positioned within said column, a commutator switch drivably connected to said drive means, and in circuit with said motor, said commutator switch being constructed and arranged to open the motor circuit upon preselected angular movement of said drive means in either direction, an anchor, torsional means connecting said drive means with said anchor, clutch means for rendering said torsional anchor ineffective, and means for shunting said commutator switch, whereby said basket may at will be caused to oscillate or rotate continuously in one direction.

20. In a washing machine, a base, an upstanding tubular column, a tub mounted around said column, a wash containing basket journaled around said column, drive means extending through the column and connected to said basket for rotation therewith and supporting thereof, an induction motor in the base having starting means, a resilient connection from the motor to said basket, an anchor, a torsional means connecting said drive means with said anchor, a commutator drivably connected to said drive means having an arcuate contact segment, a stationary brush and circuit means for said motor including said brush and segment, and means for rendering said torsional anchor ineffective and for shunting said brush and segment.
